ACTUATING MECHANISM FOR CALCULATING MACHINES

Robert E. Boyden, Berkeley, Calif., assignor to
 Marchant Calculating Machine Company, a
 corporation of California

Application July 15, 1940, Serial No. 345,516

11 Claims. (Cl. 235—79)

The present invention relates to improvements in calculating machines, and relates particularly to differential actuating mechanism for the accumulator register of such machines.

The present improvements are disclosed as embodied in the commercially known "Marchant" calculating machine described in the Avery patent application Serial Number 84,927, filed June 12, 1936, and since matured into Patent 2,271,240, issued on January 27, 1942, to which reference may be had for a complete disclosure to related mechanisms not specifically disclosed herein; it being noted that reference numerals corresponding to those appearing in said patent are applied to all corresponding parts shown but not specifically described herein.

In the calculating machine disclosed in the aforesaid patent, the value to be entered into the accumulator is set into the machine by depressing selected numeral keys of the keyboard, and when the machine begins to operate, the differential actuating mechanism is power set under control of the depressed keys before the actuating cycle starts. In the machine embodying the improvements herein disclosed, however, the differential actuating mechanism is directly set by depressing the keyboard keys, thereby eliminating a great many parts and simplifying the mechanism without sacrificing any of the advantageous features of the machine.

A primary object of the invention is the provision of a differential actuating mechanism for machines of the class described, which is adapted for economical commercial production, and which makes possible the elimination of a substantial number of parts, formerly deemed essential.

It is a further object of the invention to provide a differential actuating mechanism for machines of the class described, which may be directly set by the depression of the keys of the keyboard, but which will retain the important advantageous features of the mechanism upon which it is an improvement.

A more specific object of the invention is the provision of a key set differential actuating mechanism of the class described which may be set by the keys with a minimum of effort on the part of the operator.

Other objects will appear during the following detailed description of a preferred form of the invention, reference being made to the accompanying drawings forming a part of this specification, in which:

Figure 1 is a longitudinal sectional view of the value selecting and differential actuating mechanisms, as viewed from the right;

Figure 2 is a detailed sectional view of the means for locking the register drive gears in a centralized position, as viewed from the right;

Figure 3 is a detailed sectional view of the means for locking the value selecting mechanism, as viewed from the right;

Figures 4 and 5 are sectional views of the actuator drive unit, as viewed from the right, showing the gears which drive the pinion rods, and the means for locking the parts in alignment;

Figure 6 is a right side view, in detail, of the mechanism for rocking a shaft which controls certain locking pawls;

Figure 7 is a schematic view showing the relation of the various units to the driving means;

Figure 8 is a fragmentary schematic view of the pinion rods showing how the driving sections of these pinion rods are staggered to prevent interference; and

Figure 9 is a right side view, partly in section, of a modified form of the selection mechanism and differential actuating mechanism.

20 The machine is provided with a keyboard, described in the aforesaid Avery patent, comprising keys 100 (Figure 1) which are normally maintained in raised position by spring 102. When any key is depressed, the bottom of its stem 103 moves a bar 120 laterally a given amount depending upon the value of the key depressed. This imparts a proportionate movement to a stud 163 to which bar 120 is connected, and rocks a segmental lever 132 about a shaft 137. 25 Through a segment 138 and pinion 145 a check dial 140 is thus rotated about its shaft 141, thereby indicating the value of the key depressed.

One such segmental lever 132 is provided in each decimal order of the machine and on a rearwardly extending arm 11 thereof is formed a second gear segment 12, which meshes with a gear 13 freely mounted on a shaft 14. Mounted for rotation with each gear 13 is a selection sector 15, on which is mounted a planetary gear 16, so that when the segmental lever 132 is rocked counter-clockwise the gear 13 and sector 15 rock clockwise about shaft 14 until gear 16 is aligned with one of a series of transversely disposed pinion rods 1 to 9.

As shown in Figure 1, the pinion rods 1 to 9 are in their normal position, out of the path of movement of gear 16, so that if the number "1" key 100 is depressed, the gear 16 will be aligned with the pinion rod 1; depression of the number "2" key will align gear 16 with pinion rod 2, and so on up to the number "9" key 100 which, when depressed, aligns gear 16 with the pinion rod 9. Thus, the selecting mechanism sets the actuating mechanism to effect entry of a selected value into the accumulator.

Means are provided to lock the selecting mechanism in set position so that even though the depressed key is inadvertently released or another key is depressed during a calculation, the

selection will remain fixed until the actuation is completed.

In each order of the machine, and keyed to a shaft 29, is a cam 40 (Figure 3) which is in the plane of tips 41 and 42 of a pawl 45, one of which is also provided in each order and each of which has a lateral extension 46 formed on the downwardly extending arm thereof. When shaft 29 is rocked clockwise, as hereinafter described, the cam 40 engages the tip 41 and rocks the pawl 45 counter-clockwise until the lateral extension 46 seats between the teeth 19 of the selection sector 15, thus locking the selecting mechanism.

Each end of pinion rods 1 to 9 (Figure 1) is turned down to form bearings 17 adjacent the opposite ends thereof which are received in cam slots 21 in two end plates 20 rockable about shaft 14 as a center. Parts of the pinion rods 4 and 5 are shown as cut away in Figure 1, to make it clear that when the plate 20 is rocked clockwise, the edges of the slots 21 cam the pinion rods 1 to 9 radially toward shaft 14, said rods being guided in their movement by radial slots 18 in a stationary plate 19. In this manner one of the pinion rods is enmeshed with each of the set gears 16 and a driving connection is established to a gear 30 in each order through sun gears 27 in each order, which are rotatably mounted on shaft 14, and mesh with gears 28 rotatable on a shaft 29 and secured to the respective drive gears 30.

The rocking of plate 20 for this purpose is effected concurrently with the lowering and raising of the dipping carriage which supports the accumulator, and since the mechanism for effecting such movements of the dipping carriage is described in detail in the aforesaid Avery patent, no detailed description thereof need be given here. In general, the dipping carriage comprises a series of plates 266 pivotally mounted on a shaft 262 fixed in the carriage, and connected at their opposite end by a bail 269. Cross shafts supported in the plates 266 carry the accumulator register mechanism comprising numeral wheels 279 with their drive gears 273 which mesh with intermediate drive gears 271 adapted to mesh with gears 30 of the actuating mechanism when plates 266 are rocked clockwise about shaft 262.

Bail 269 is engaged by rollers 568 mounted on carriage dipping links 566 which are guided for vertical movement by studs 567 and reciprocated by the mechanisms described in detail in the aforesaid Avery patent, to enmesh gears 271 and 30 in each order before the actuating mechanism is operated, and to demesh said gears after the actuating mechanism has been arrested. For the purpose of effecting the above described radial movements of the pinion rods 1 to 9 concurrently with the dipping and raising of the dipping carriage, a cross shaft 23 is extended between the links 566 which are disposed adjacent opposite sides of the machine, and a slot 22 in each plate 20 embraces said shaft, the arrangement being such that when gears 271 are moved into mesh with gears 30, the pinion rods 1 to 9 will be moved radially toward shaft 14, and vice versa.

Cyclically operated means are provided to rotate the several pinion rods 1 to 9, inclusive, different amounts during each cycle, whereby entry of values from 1 to 9 may be effected. Obviously a great many systems of gear ratios can be devised, but the one found most readily adaptable to the "Marchant" calculating machine is illustrated in Figures 4, 5, and 7.

Mounted on the pinion rod 1 is a twenty tooth gear 66 which is connected to the eight tooth pinion rod 14 by an idler 56, the ratio being such that for each quarter turn of rod 14, the ten tooth rod 1 will rotate an angular distance of one tooth.

The pinion rod 2 has ten teeth and is connected to the eight tooth pinion rod 14 by an idler 61, the ratio being such that for each quarter turn of rod 14, rod 2 will rotate an angular distance of two teeth.

Mounted on the pinion rod 3 is a twenty tooth gear 67 which is connected to a twenty-four tooth gear 52 on rod 14 by an idler 57, the ratio being such that for each quarter turn of rod 14, the ten tooth rod 3 will rotate an angular distance of three teeth.

Mounted on the pinion rod 4 is a twenty tooth gear 68 which is connected to a thirty-two tooth gear 55 on rod 14 by an idler 62, the ratio being such that for each quarter turn of rod 14, the ten tooth rod 4 will rotate an angular distance of four teeth.

Mounted on the pinion rod 5 is an eighteen tooth gear 69 which is connected to a thirty-six tooth gear 53 on rod 14 by an idler 58, the ratio being such that for each quarter turn of rod 14, the ten tooth rod 5 will rotate an angular distance of five teeth.

The pinion rod 6 has ten teeth and is connected to the twenty-four tooth gear 52 on rod 14 by an idler 63, the ratio being such that for each quarter turn of rod 14 the ten tooth rod 6 will rotate an angular distance of six teeth.

The pinion rod 7 has ten teeth and is connected to a twenty-eight tooth gear 54 on rod 14 by an idler 59, the ratio being such that for each quarter turn of rod 14, rod 7 will rotate an angular distance of seven teeth.

The pinion rod 8 has ten teeth and is connected to the thirty-two tooth gear 55 on shaft 14 by an idler 64, the ratio being such that for each quarter turn of the rod 14, rod 8 will rotate an angular distance of eight teeth.

The pinion rod 9 has ten teeth, and is connected to the thirty-six tooth gear 53 on rod 14 by an idler 60, the ratio being such that for each quarter turn of rod 14, rod 9 will rotate an angular distance of nine teeth.

This may be tabularly summarized as follows:

Table

Selected value	1	2	3	4	5	6	7	8	9
Number of teeth pinion rod is driven	1	2	3	4	5	6	7	8	9
Number of teeth in drive gear on shaft 14	8	8	24	32	36	24	28	32	36
Number of teeth advanced in one cycle ($\frac{1}{4}$ turn of shaft 14)	2	2	6	8	9	6	7	8	9
Number of teeth in driven gear on pinion rod	20	10	20	20	18	10	10	10	10

The gears shown in Figures 4 and 5 are separated into two figures to clarify the showing. The true lateral arrangement, however, is represented schematically in Figure 7, in which it may be seen that the drive starts with the motor 640, extends through the coupling 642, slip clutch 644, pinion 645, compound idlers 646 and 647 through gears 362, 650, and 415 to the main clutch 428 which makes a half rotation for each cycle and thence to shaft 419, reverse clutch 450, and gear 50, as described more completely in the aforesaid Avery patent. Meshing with the gear 50 is another gear 51, having twice the number

of teeth, which is splined to a pinion rod 14 serving as a driving pinion and shaft for the drive unit, and making a quarter turn for each cycle of operation of the main clutch 428.

The operation of the actuating mechanism by main clutch 428 is effected in the manner described in detail in the aforesaid Avery patent and need not be described herein.

After the actuating cycle has terminated the pinion rods 1 to 9 are moved outwardly so the gear 16 may be revolved to a new selection, and the gears 271 are raised so the carriage may be shifted laterally or the numeral wheels 279 turned to zero. This is accomplished by the mechanism described in detail in the aforesaid Avery patent which releases the latches restraining links 566 (Figure 1) and allows the springs 569 to raise the links 566 and return all parts to the position shown in this figure.

To release the selection levers 15 after actuation is terminated so that a new setting can be made, shaft 29 is returned to the position shown in Figure 3, and during its movement cam 40 engages the tip 42 of each lever 45 and rocks said lever and its tip 46 clockwise about shaft 82 and clear of the teeth of the selection levers 15.

To hold gears 271 and 30, pinion rods 1 to 9, and the drive train in correct alignment, additional pawls and locking devices are provided.

Gears 271 (Figure 1) are normally held by pawls 319 releasable by dipping of the dipping carriage, as described in the aforesaid Avery patent. Thus the gears 271 in the carriage are held in proper alignment until they are engaged with gears 30.

Adjacent each gear 30 and keyed to shaft 29 is a second cam 70 (Figure 2) which lies in the plane of a pawl 71, freely rockable on the adjacent shaft 14. When cam 70 is in its normal position, as shown, it holds the nose 72 of pawl 71 between the teeth of gear 30 to retain gears 30, 28, 27, and 16 in correct alignment, whereby gear 16 is held in correct position to mesh with the pinion rods 1 to 9. The nose 73 of pawl 71 extends circumferentially of cam 70 so that it will be held by cam 70 until the very last part of the movement of shaft 29, so that the gears 271 may be partly enmeshed with gears 30 before the latter is released by pawl 71.

Means are provided to lock pawls 71 in engagement with their gears 30 in all orders in which no key 100 is depressed. Each of the selection sectors 15 is provided with a stud on which gears 16 rotate and this stud is provided with an extension 74 (Figures 1 and 2) which is held in the position shown in Figure 2 by spring 164 when no key 100 in its order is depressed. Extension 74 (Figure 1) presses against pawl 71 holding it in engagement with gear 30 during the rocking of shaft 29 which, by finally engaging lateral extension 46 of lever 45 with the same selection sector 15, holds the latter locked in zero position and thus holds extension 74 locked against pawl 71 in engagement with gear 30.

Means are also provided to align pinion rods 1 to 9 for engagement with gears 16 and the idler gears 56 to 64 of the drive unit. In Figures 4 and 5 the parts are shown in their operative position. After operation of the actuating mechanism is completed, however, the pinion rods are moved radially outwardly from shaft 14 and one is shown in its outward position by the dotted outline 8a (Figure 5). A stationary plate 76 is provided with nine pairs of extensions 77, one of which lies in the path of such radial

movement of each pinion rod so that when said rods are moved outwardly, a tooth of each is engaged between the tips of a pair of the extensions 77 before it is entirely free from its respective idler, and is thus retained in correct alignment until again enmeshed with the idlers 56 to 64 and planetary gear 16 (Figure 2).

Means are also provided to align and lock and unlock the drive unit prior and subsequent to the actuating cycle. Shaft 29 is shown in Figure 5 in the position it assumes during the actuating cycle, having been rocked clockwise approximately 90° from the position in which it is shown in Figures 2 and 3, to allow the pawl 80 to be rocked clockwise away from the gear 55 and thus allow the drive unit shown in Figures 4 and 5 to operate. After the actuating cycle, however, the shaft 29 is rocked counter-clockwise to the position in which it is shown in Figures 2 and 3, and the cam 81 then rocks a pawl 80 counter-clockwise about a shaft 82 until the nose 83 engages between the teeth of gear 55 and locks the entire unit, including the idlers 56 to 64, in alignment.

The mechanism for effecting the rocking movements of shaft 29, heretofore described, comprises a lever 25 (Figure 6) rockable on shaft 225 by a cam 35 on the setting clutch shaft 431, and provided with a gear segment 226 formed on an arm thereof, so that upon each cyclic operation (half rotation) of shaft 431, lever 25 will be rocked clockwise.

Lever 25 operates shaft 29 by means comprising meshed gears 36 and 37, the latter of which is (Figure 6) fixed to shaft 29 so that upon clockwise movement of lever 25, shaft 29 will be rocked clockwise approximately 90°.

The cam 35 is proportioned so that this movement will be divided into two parts: i. e., a slight clockwise movement of shaft 29, sufficient to effect engagement of the selection lock will be effected when the shaft 431 commences to rotate counter-clockwise; then shaft 29 will remain stationary until shaft 431 has nearly completed its cycle; and finally, a further clockwise movement of shaft 29, sufficient to disengage the pawls of gears 30 and the drive unit lock pawl, will be effected during the last part of the cycle of shaft 431.

The shaft 29 is held in the position to which it is moved in this manner by a latch 575a which corresponds in construction and mode of operation to the carriage latch 575 (Figure 1) being pivotally mounted on the same shaft 576 and adapted to be rocked to release the lever 25 by an arm 539a fixed to the same shaft 581 to which the releasing arm 539 for the carriage latch is fixed and provided with a similar ear 583a for engaging an extension of the latch 575a. A spring 579a maintains the latch 575a in position to engage an ear 25a on lever 25 and prevent counter-clockwise movement of said lever until latch 575a is released by the rocking of shaft 581.

A spring 38 tensioned between the lever 25 and the machine frame tends to rock the shaft 29 counter-clockwise, and the above described movements of shaft 29 will therefore take place in reverse direction when the latch 575a is released.

As hereinbefore described, shaft 29 carries three kinds of cams for actuating separate pawling devices; cams 40 (Figure 3) for actuating the pawls for locking selection sectors 15; cams 75 70 (Figure 2) for actuating the pawls for locking

gears 36; and a cam 31 (Figure 5) for actuating the pawl 28 for locking the drive unit. It is important that these pawling devices operate in a predetermined sequence, especially after termination of an actuating cycle, so as to take backlash out of the gear trains in a predetermined direction, and this may be taken care of by proper proportioning of these cams.

At the termination of an operation of the actuating mechanism, the pawl 28 is first actuated to align and lock gear 55; then pawls 71 are actuated to align and lock gears 30; and finally pawls 319 are released so that they will engage and align gears 271. In this way the backlash is taken out in one direction. After this is done, levers 45 are actuated to unlock the selecting mechanism.

For this purpose, the cams 31, 70, and 40 are so proportioned that cam 31 (Figure 5) will engage and rock pawl 28 into engagement with gear 55 during the very first part of the counter-clockwise movement of shaft 29, before cams 70 have engaged pawls 71 and before the dipping carriage has begun to rise, rising of the carriage being prevented after release of latches 575 by the presence of the high portion of cam 596. (Figure 1) between the arm 597 and the shaft 595, as described in the aforesaid Avery patent. Cams 70 are so proportioned as to engage and rock pawls 71 into engagement with gears 30 during the very next part of this rocking movement of shaft 29, after pawl 30 has engaged gear 55, but still before the dipping carriage has begun to rise. Thereafter the cam 596 rotates sufficiently to allow the dipping carriage to rise sufficiently to permit engagement of said pawls 319 with gears 271, and during the last part of the movement of shaft 29 cams 40 rock levers 45 to unlock the selection sectors 45.

When the dipping carriage is again lowered, the operation of these parts of course takes place in the reverse order, and it will be noted that since the selection lock 45 is made effective during the very first part of the cycle of shaft 431, the planetary gears 16 will be definitely and properly aligned before the pinion rods 1 to 9 are moved into mesh with them.

Modified embodiment

As shown in the alternative construction illustrated in Figure 9, the pinion rods may be mounted on fixed axes and the selection made by rolling each planetary gear over the pinion rods to a position in which it is enmeshed with a pinion rod corresponding to the key depressed. Each pinion rod is rotated a whole number of teeth during each actuating cycle, and therefore always stops with a tooth in correct alignment to form a composite internal rack composed of the inwardly protruding teeth of the entire series of pinion rods. Each planetary gear can thus rotate on its own axis as it revolves out of mesh with one pinion rod and into mesh with the next.

The selection mechanism shown in Figure 9 is generically the same as that in the first embodiment, and comprises, in each order, ten equally spaced keys 100 consecutively numbered 0 to 9, the stems 103 of which overlie a selection bar 133 which is differentially positioned longitudinally upon depression of a key. The notches 131 are so spaced in the embodiment illustrated in Figure 9, however, that if a number 1, 2, 3, or 4 key 100 is depressed, the bar 133 is moved 1, 2, 3, or 4 increments respectively to the right from the zero position (as viewed in Figure 9), while if a

number 5, 6, 7, 8, or 9 key is depressed, the bar 133 is moved 1, 2, 3, 4, or 5 increments, respectively, to the left.

These rightward or leftward movements of bar 133 effect clockwise or counter-clockwise rocking of the segmental lever 210 freely mounted on shaft 37 and provided with a segment 211 which meshes with the pinion 145. A check dial 212 is made integral with said pinion and is rotated therewith on shaft 141 to indicate to the operator the value of the key 100 depressed.

Segmental lever 210 is provided with a second segment 213 enmeshed with a third segment 214 which is rockably mounted on shaft 215. Mounted for rotation with segment 214 is a plate 216 on which are provided planetary gears 218 and 219, and a planetary idler 220.

Ten pinion rods 200 to 209, inclusive, are located arcuately about shaft 215, the last digit of the reference numerals 200 to 209 indicating the angular advance of each of these shafts during an actuating cycle; i. e., shaft 200 is stationary, pinion rod 201 rotates one tooth per actuating cycle, pinion rod 202 two teeth, et cetera.

25 A sun gear 221 mounted on shaft 215, meshes with planetary gear 220 and has a pitch radius equal to half the radius of an arc drawn tangent to the pitch circle of gears 218 and 201 to 209; and furthermore, planetary gears 218 and 219 constitute a two-to-one compound ratio. From this it will be seen that when the planetary gear 218 revolves about shaft 215, this movement is compensated by rotation on its own axis in the opposite direction, and can be traced as follows: if a number 5 to number 9 key is depressed, the plate 216 is rocked counter-clockwise, the gear 220 is rotated counter-clockwise as it revolves about sun gear 221, and gears 218 and 219 rotate clockwise as they revolve about shaft 215 in a counter-clockwise direction.

30 Pawling devices substantially similar to those illustrated and described in connection with the first described embodiment are provided but not shown in Figure 9. Selection locking is effected by a lever 231 pivotally mounted on a shaft 232 and provided with a roller 233 adapted to enter aligning notches 234 on the selection sector 216 when the lever 231 is rocked, against the tension of spring 235, by a roller 231a on lever 570.

35 The pinion rods 201 to 209 are driven amounts proportional to the digits 1 to 9 by a suitable unit fundamentally the same as that shown in Figures 4 and 5 of the first embodiment. The drive is transmitted from the pinion rods through gears 218, 219, 220, 221, to compound idlers 222, 223, which drive the accumulator register in the same manner as described in the aforementioned Avery patent, the gear 223 corresponding to the gear 189 of said patent.

40 As described in the aforesaid Avery patent, the keys 100 are released during a setting clutch cycle. Therefore, means are provided to return said segmental lever 210 and plate 216 to a zero position after actuation is completed. As described hereinbefore, the selection lock is released after termination of the operation of the actuating mechanism. A spring 150, tensioned between a stud 152 attached to the segmental lever 210 and a stationary stud 151, tends to maintain stud 152 in alignment with shaft 37 and stud 151, but when the bar 133 and lever 210 have been moved only one or two increments in either direction the effect of spring 150 is not sufficient to insure return of the part to zero. 45 Therefore, a lever 155 is pivoted on shaft 141 and

provided with a stud 156 which is adapted to engage the camming surfaces 157. A spring 158 is tensioned between stud 156 and 137 so that when the lever 210 is rocked only slightly in either direction, the spring 158 urges the stud 156 against one of the camming surfaces 157 to effect a return of the setting mechanism to zero.

To prevent stud 156 from restraining segmental lever 120 during the initial part of the setting, the lock bar 117, as described in the aforesaid Avery patent, is moved rearwardly during the first part of the key depression, and in so doing engages the arm 159, thereby rocking the lever 155 counter-clockwise to render the segmental lever 210 free from the restraint of stud 156.

The spacing of the pinion rods preferably is compressed to the extent shown in Figure 9 to minimize the movement of the planetary gear 218 during setting, but Figure 8 shows that the driving parts of the pinion rods are staggered and very narrow, to avoid interference. Although the parts 201, 202, 203, et cetera, are shown in this embodiment as pinion rods which are turned down in sections, it is obvious that they could be merely spur gears keyed to a shaft and located by spacers.

Since other modifications in the embodiment disclosed herein will occur at once to those skilled in the art, the invention is not to be considered as restricted to the embodiments shown and described except as required by the prior art and by the spirit of the appended claims.

I claim:

1. In a calculating machine having ordinarily arranged registering mechanism, a settable differential actuating mechanism comprising, in combination; ordinarily arranged gears for actuating said registering mechanism, a series of parallel shafts arranged with their axes intersecting a common circle, ordinarily arranged gears on said shafts, cyclically operable means for driving said shafts in the same direction, each at a different rate, means for arresting said driving means in full cycle position, means for connecting any one of the ordinarily arranged gears on said shafts with a corresponding one of said ordinarily arranged actuating gears including ordinarily arranged selection gears meshing with said actuating gears respectively and each orbitally movable about the rotational axis of one of said actuating gears at the center of the circle intersected by the axis of said shafts into radial alignment selectively with one of said ordinarily arranged gears on said shafts, and means for preventing rotational movement of said actuating gears during orbital movement of said selection gears.

2. In a calculating machine having ordinarily arranged registering mechanism, a settable differential actuating mechanism comprising, in combination; ordinarily arranged gears for actuating said registering mechanism, a series of parallel shafts arranged with their axes intersecting a common circle, ordinarily arranged gears on said shafts, cyclically operable means for driving said shafts in the same direction, each at a different rate, means for arresting said driving means in full cycle position, and ordinarily arranged means for connecting any one of said ordinarily arranged gears on said shafts with a corresponding one of said actuating gears including, in each order, a selection member pivotally mounted centrally of said circle, an orbitally movable gear rotatably mounted on said mem-

ber and movable thereby to any of a series of positions in which its center lies on a radius of said circle intersecting the axis of one of said shafts, a central gear rotatably mounted centrally of said circle, means for transmitting rotational movement of said orbitally movable gear through said central gear to one of said actuating gears, and means for preventing rotational movement of said actuator gears during orbital movement of said selection gears.

3. In a calculating machine having ordinarily arranged registering mechanism, a settable differential actuating mechanism comprising, in combination; ordinarily arranged gears for actuating said registering mechanism, a series of parallel shafts arranged with any three of their axes intersecting a common circle, ordinarily arranged gears on said shafts, cyclically operable means for driving said shafts in the same direction, each at a different rate, means for arresting said driving means in full cycle position, means for connecting any one of said shafts with each of said actuating gears including a member in each order movable about the center of said circle and selectively settable into driving engagement with a gear on any one of said shafts, and means for rendering said member ineffective to move said actuating gear upon movement of said member from a position to be driven by any one of said shaft gears to a position to be driven by any other of said shaft gears.

4. In a calculating machine having ordinarily arranged registering mechanism, a settable differential actuating mechanism comprising, in combination; ordinarily arranged gears for actuating said registering mechanism, a series of parallel shafts arranged with their axes intersecting a common circle, ordinarily arranged gears on said shafts, cyclically operable means for driving said shafts each at a different rate, ordinarily arranged means for connecting any one of said shafts with each of said actuating gears including, in each order, a selection member pivotally mounted centrally of said circle, an orbitally movable gear rotatably mounted on said member and movable thereby in mesh with the gears on said shafts to a series of positions, a central gear rotatably mounted centrally of said circle, means for transmitting rotational movement of said orbitally movable gear through said central gear to one of said actuating gears, and means responsive to pivotal movement of said selection member for compensating the rotational movement of said orbitally movable gear effected by orbital movement thereof in mesh with the gears on said shafts to prevent transmission of such rotational movement to said central gear.

5. In a calculating machine having ordinarily arranged registering mechanism, a settable differential actuating mechanism comprising, in combination; ordinarily arranged gears for actuating said registering mechanism, a series of parallel shafts arranged with their axes intersecting a common circle, ordinarily arranged gears on said shafts, cyclically operable means for driving said shafts each at a different rate, means for arresting said driving means in full cycle position, and means for connecting any one of said ordinarily arranged gears on said shafts with a corresponding one of said actuating gears including ordinarily arranged selection gears each orbitally movable within the circle intersected by the axes of said shafts, and means for mov-

ing said shafts radially in respect to said common circle to bring the ordinarily arranged gears thereon into mesh with said selection gears.

6. In a calculating machine having ordinarily arranged registering mechanism, a settable differential actuating mechanism comprising, in combination; ordinarily arranged gears for actuating said registering mechanism, a series of parallel shafts arranged with their axes intersecting a common circle, ordinarily arranged gears on said shafts, cyclically operable means for driving said shafts each at a different rate, means for arresting said driving means in full cycle position, ordinarily arranged means for connecting any one of said ordinarily arranged gears on said shafts with a corresponding one of said actuating gears including, in each order, a selection member pivotally mounted centrally of said circle, an orbitally movable gear rotatably mounted on said member and movable thereby to any of a series of positions in which its center lies on a radius of said circle intersecting the axis of one of said shafts, and a central gear rotatably mounted centrally of said circle and effective to transmit rotational movement of said orbitally movable gear to one of said actuating gears; means for moving said shafts radially with respect to said common circle to bring the ordinarily arranged gears thereon into mesh with said orbitally movable gears.

7. In a calculating machine having ordinarily arranged registering mechanism, a settable differential actuating mechanism comprising, in combination; ordinarily arranged gears for actuating said registering mechanism, a series of parallel shafts arranged with their axes intersecting a common circle, ordinarily arranged gears on said shafts, means for moving said shafts radially with respect to said common circle, cyclically operable means for driving said shafts each at a different rate, means for arresting said driving means in full cycle position, means for connecting any one of said ordinarily arranged gears on said shafts with a corresponding one of said actuating gears including ordinarily arranged selection gears each orbitally movable within the circle intersected by the axes of said shafts, and means for first actuating the aforesaid means for moving said shafts radially of said circle to effect driving engagements between said ordinarily arranged gears on said shafts and said selection gears and for thereafter actuating the aforesaid cyclically operable means for driving said shafts.

8. In a calculating machine having ordinarily arranged registering mechanism, a settable differential actuating mechanism comprising, in combination; ordinarily arranged gears for actuating said registering mechanism, a series of parallel shafts arranged with their axes intersecting a common circle, ordinarily arranged gears on said shafts, a plurality of fixed supporting plates for said shafts having slots embracing said shafts and extending radially of said circle, a plurality of movable plates rockable about the center of said circle and having slots embracing said shafts and extending angularly with respect to the slots in said fixed plates, cyclically operable means for driving said shafts each at a different rate, means for arresting said driving means in full cycle position, means for connecting any one of said ordinarily arranged gears on said shafts with a corresponding one of said actuating gears including ordinarily arranged selection gears each orbitally movable within the circle intersected by the axes of said shafts, and means for first rocking said

movable plates to move said shafts radially of said circle and effect driving engagements between said ordinarily arranged gears on said shafts and said selection gears, and for thereafter actuating the cyclically operable means for driving said shafts.

9. In a calculating machine having ordinarily arranged registering mechanism, a settable differential actuating mechanism comprising, in combination; ordinarily arranged gears for actuating said registering mechanism, a series of parallel shafts arranged with their axes intersecting a common circle, ordinarily arranged gears on said shafts, a plurality of fixed supporting plates for said shafts having slots embracing said shafts and extending radially of said circle, a plurality of movable plates rockable about the center of said circle and having slots embracing said shafts and extending angularly with respect to the slots in said fixed plates, cyclically operable means for driving said shafts each at a different rate, means for arresting said driving means in full cycle position, ordinarily arranged means for connecting any one of said ordinarily arranged gears on said shafts with a corresponding one of said actuating gears including, in each order, a selection member pivotally mounted centrally of said circle, an orbitally movable gear rotatably mounted on said member and movable thereby to any of a series of positions in which its center lies on a radius of said circle intersecting the axis of one of said shafts, and a central gear rotatably mounted centrally of said circle and effective to transmit rotational movement of said orbitally movable gear to one of said actuating gears; and means for first rocking said movable plates to move said shafts radially of said circle and effect driving engagements between said ordinarily arranged gears on said shafts and said selection gears, and for thereafter actuating the cyclically operable means for driving said shafts.

10. In a calculating machine, a settable differential actuating mechanism comprising, in combination; an actuating gear, a series of transmission gears arranged with their axes intersecting a common circle, cyclically operable means for driving said transmission gears in the same direction, each at a different rate, means for arresting said driving means in full cycle position, means for connecting any one of said transmission gears with said actuating gear including a selection gear orbitally movable within the circle intersected by the axes of said transmission gears and means for rendering said selection gear ineffective to move said actuating gear upon orbital movement of said selection gear from a position to be driven by any one of said transmission gears to a position to be driven by any other of said transmission gears.

11. In a calculating machine, a settable differential actuating mechanism comprising, in combination; an actuating gear, a series of transmission gears arranged with their axes intersecting a common circle, means for moving said transmission gears radially with respect to said common circle, cyclically operable means for driving said transmission gears, each at a different rate, means for arresting said driving means in full cycle position, and means for connecting any one of said transmission gears with said actuating gear including a selection gear orbitally movable within the circle intersected by the axes of said transmission gears.

ROBERT E. BOYDEN.
